UNITED STATES PATENT OFFICE.

EMILE SCHEEMACKER AND GEORGES RAIMOND OF WOONSOCKET, RHODE ISLAND.

CIRCUIT CONTROLLER.

Application filed August 14, 1923. Serial No. 657,383.

The present invention relates to circuit controllers of the thermostatic type and adapted to be placed in rooms or other locations where dangerous heat or combustion 5 may take place, and which will sound an alarm under such circumstances.

The object is to provide a very simple article of manufacture that will close a circuit so as to sound an alarm or otherwise 10 operate a signal when dangerous heat conditions arise.

The preferred embodiment of the invention is illustrated in the accompanying drawings, wherein:—

15 Figure 1 is a side elevation of the apparatus,

Figure 2 is a view in elevation with the front plate of the casing removed,

20 Figures 3, 4 and 5 are detail sectional views respectively on the lines 3—3, 4—4 and 5—5 of Figure 2,

Figures 6 and 7 are respectively sectional views on the lines 6—6 and 7—7 of Figure 1.

In the embodiment disclosed, a suitable 25 casing is employed, comprising spaced front and rear plates 8 and 9, forming an open housing. Within this casing is located a thermostatic element 10 in the form of a coiled spring, the inner end of which is 30 mounted on a shaft 11 journaled in the front and rear plates 8 and 9. Mounted on the rear plate is a block 12 of insulating material, supporting a contact element 13, the upper end of which is in the form of a cup 35 that contains mercury 14.

A post 15, supported on the block 12, but grounded on the casing, constitutes a mounting for a lever 16 that is fulcrumed between its ends on said post. One end of this lever 40 has a downturned terminal 17 that is adapted to move into and out of the mercury 14 of the cup. The other end extends toward the coiled spring 10. The shaft 11 on which said spring is mounted carries a 45 crank arm 18, the terminal of which is forked as shown at 19, this forked end being adapted to operate against the arm of the lever 16 opposite to that carrying the terminal 17. Preferably also the shaft is provided with a counterweight arm 20.

The outer plate 8 of the casing is provided with an arcuate slot 21, in which is slidably mounted a post 22, and the inner end of this post is received by an eye 23 formed on the

outer end of the spring 10. The post may be 55 provided with a clamping nut 24, but as the instrument in many cases is placed at the top of the room, said post has connected thereto a downwardly extending link 25 that is connected to another post 26 slidable 60 in a vertical slot 27 formed in the face plate of a thermometer 28. This thermometer is provided with the usual gage scale 29 and the post 26 carries a pointer 30 movable along said scale. The post 26 also has a 65 clamping nut 31.

With this construction it will be obvious that the tension of the spring 10 can be varied as desired by moving the post 26 up or down, this moving the link 25, moves the 70 post 22, and thereby increases or decreases the tension of the spring 10. Assuming the parts as shown in Figure 2, normally the terminal 17 of the lever 16 is out of contact with the mercury 14 in the cup 13. If, 75 however, an unusual or dangerous degree of temperature occurs, the spring 10 will automatically operate to turn the shaft 11, thereby turning the crank 18 and causing its forked end 19 to engage the lever 16 and 80 swing it until the terminal 17 is in the mercury. If, now, the cup 13 and the casing is placed in an electric circuit containing an alarm, it will be obvious that the circuit 85 will be closed and the alarm actuated. The 90 relation of the parts is such that by moving the pointer 30 to the different degrees indicated on the thermometer the alarm will be sounded when that degree of temperature is approximately reached.

From the foregoing, it is thought that the construction, operation and many advantages of the herein described invention will be apparent to those skilled in the art without further description and it will be understood that various changes in the size, shape, proportion and minor details of construction may be resorted to without departing from the spirit or sacrificing any 95 of the advantages of the invention.

Having thus fully described our invention, what we claim as new, and desire to secure by Letters Patent, is:—

A circuit controller comprising a housing, a mercury cup terminal mounted in the 105 housing, a shaft journaled in the housing at one side of the cup, a lever fulcrumed between its ends in the housing between the

cup and shaft, one arm of the lever having a portion that enters the cup, the other arm extending towards the shaft, a counter-weighted arm fixed to the shaft and having a terminal yoke that receives and engages the other and adjacent arm of the lever, and a heat responsive coiled spring surrounding

the shaft and fixed thereto for turning the shaft and arm.

In testimony whereof, we affix our signatures.

EMILE SCHEEMACKER.
GEORGES RAIMOND.
